UNITED STATES PATENT OFFICE.

JOSEPH S. SHERER, OF AURORA, ILLINOIS, ASSIGNOR TO AMERICAN SUSPENDER COMPANY, OF AURORA, ILLINOIS, A CORPORATION OF ILLINOIS.

SUSPENDER-END.

SPECIFICATION forming part of Letters Patent No. 695,701, dated March 18, 1902.

Application filed November 18, 1901. Serial No. 82,694. (No model.)

To all whom it may concern:

Be it known that I, JOSEPH S. SHERER, a citizen of the United States, residing at Aurora, in the county of Kane and State of Illinois, have invented certain new and useful Improvements in Suspender-Ends, of which the following is a specification.

This invention relates to novel improvements in suspenders, and has particular reference to the means for connecting the end with the web.

One object of the invention is to provide a strong and permanent connection between the end and the cast-off and to greatly increase the strength of the cast-off by embodying therewith a smooth and lasting bearing for the end.

Another object is to facilitate the operation of the cast-off and enable the disconnection of the end and drawers-support from the web easily and at the same time and while they remain fastened to the trousers and drawers.

With these and other ends in view the invention consists of the novel construction and arrangement of parts hereinafter described, and illustrated in the accompanying drawings, in which—

Figure 1 is a front view of a portion of a suspender embodying the invention. Fig. 2 is a similar view showing the cast-off open. Fig. 3 is a sectional view. Fig. 4 is a detail view of the metal bearing.

Referring to the drawings, in which like numerals of reference denote corresponding parts in the several figures, 10 designates the web, which carries a double loop 11 of suitable character. The suspender-end 12 is connected with the web by the cast-off 13, and this cast-off consists, preferably, of a leather mounting 14, having one part 15 folded upon itself to form a loop 16 and its other part made in the form of a flap 17, which passes through the double loop 11 and is fastened to the looped end. Inside of the loop formed by the mounting I arrange a loop-bearing 18, which consists of a metal plate bent upon itself to form a loop of suitable character to receive the intermediate part of the suspender-end 12, which works easily in the loop to conform with the movement of the wearer. The back plate 23 of the metal loop is straight

throughout its length, and the upper part 24 of the front plate is arranged parallel with and adjacent to the back plate; but the lower part 25 is bulged to form the loop, whereby the looped plate may be snugly fitted in the mounting.

In the embodiment of the invention shown in the drawings the suspender-end is made of leather which has flat ends provided with buttonholes and a rounded intermediate part to work easily in the metal loop, the flat ends serving by their size and shape to prevent the suspender-end from becoming disconnected from the loop.

The cast-off is detachably connected with the web in the usual manner by means of a fastening device, which is preferably of the character of a glove-fastening, the head member 19 being carried by the flap 17 and the shank member 20 being carried by the looped part of the cast-off. This shank member is provided with a base 20' and passes through the drawers-support 21, the looped part of the cast-off, and the ends of the metal loop, which are provided with openings 22 for this purpose, and fastens these parts securely together, whereby the drawers-support and the end are permanently connected with the cast-off and the end is provided with a smooth and non-wearing bearing therein. The shank member 20 is held on the side opposite the base 20' by a washer 22' or in some other suitable manner. The cast-off is used in the ordinary manner to detach or connect the end with the web, the flap 17 carrying the fastening-head 19 and being arranged to slip easily through the loop 11 for this purpose.

The metal loop is concealed within the mounting on the cast-off and entirely protected thereby, and as the end is arranged to operate in this metal loop a permanent connection between the end and the cast-off is thereby effected. The metal loop constitutes a smooth and, to all intents and purposes, a non-wearing bearing for the end, which greatly increases the strength of the cast-off and prevents the breaking of the cast-off at the loop thereof, due to strains and constant working of the end therein.

By detachably connecting the cast-off with the web in the manner shown and described

I am able permanently connect the drawers-support and the suspender-end with the cast-off without in any way interfering with the cast-off operating in the usual manner and 5 without necessitating the unfastening of the drawers-support, thereby enhancing the usefulness of a cast-off on suspenders without changing its manner of operation or complicating its construction.

10 Having thus fully described my invention, what I claim, and desire to secure by Letters Patent, is—

15 1. The combination with the web of a suspender and a loop carried thereby, of a cast-off detachably connected therewith and comprising a mounting having its lower part looped and its upper part formed into a flap to pass through the loop on the web and be folded on and fastened to the looped part of 20 the mounting, a plate bent to form a loop and arranged within the loop of the mounting, a fastening device passing through the mounting and both ends of said plate to secure said parts together and close the loops, and a suspender-end operating in the loops of said plate and mounting.

25 2. The combination with the web of a suspender and a loop carried thereby, of a cast-off detachably connected therewith and comprising a mounting having its lower part looped and its upper part made in the form of 30 a flap to engage the loop on the web, a metal

plate bent to form a loop and arranged in the loop of the mounting with its ends extending upward, said looped plate having a straight 35 back and a bulged front to form the loop, a device passing through the mounting and both ends of the plate and securing the parts together and closing the loops, a suspender-end operating in the loops of said plate and mounting and permanently secured therein, and a fastening device for securing the flap to the looped part of the mounting.

3. The combination with the web of a suspender, of a loop carried by said web, a cast-off comprising a mounting having its lower part looped, a looped metal plate arranged in the loop of the mounting the upper part of the mounting being formed into a flap to pass through the loop on the web and be folded on 45 the looped part of the mounting, a drawers-support, and a fastening device comprising a head member carried by the flap and a shank member passing through the drawers-support, the looped part of the mounting and the ends 50 of the metal loop therein, and a suspender-end operating in said metal loop and permanently connected with the cast-off, substantially as described.

JOSEPH S. SHERER.
